UNITED STATES PATENT OFFICE.

WILLIAM GOODROW, OF CHICAGO, ILLINOIS.

FRAME CORNER AND FASTENER.

No. 909,080.

Specification of Letters Patent.

Patented Jan. 5, 1909.

Application filed May 7, 1907. Serial No. 372,322.

To all whom it may concern:

Be it known that I, WILLIAM GOODROW, a citizen of the United States, residing at Chicago, in the county of Cook and State 5 of Illinois, have invented certain new and useful Improvements in Frame Corners and Fasteners, of which the following is a specification.

The present invention is primarily designed for interlocking the abutting corners of picture frames, but can be used for interlocking other frames where a close and perfect joint is desired or required.

The objects of the invention are to hold 15 the abutting corners of the frame against front and rear slipping, and to draw the abutting edges of the corners in close contact, so as to form a perfect and complete joint; to construct a draw staple adapted 20 to be entered into receiving holes of the frame pieces on each side of the corner joint, for the legs of the staple to act and draw together the abutting faces of the pieces at the corner; to form, in the end face of one 25 piece at the corner, a tongue, and in the opposing face of the other piece at the corner, a groove to receive the tongue and hold the pieces in alinement and against slipping forward or backward out of place; to construct 30 a locking staple, for the corner of a frame, of spring metal or material, with the legs of the staple slightly inclined inward, and with the ends of each staple formed so as not to interfere with the forcing or driving 35 of the staple to locking position; and to improve generally the interlocking tongue or groove, and the locking staple, for making a tight joint at the corners of the frame.

The invention consists in the features of 40 construction and combinations of parts hereinafter described and claimed.

In the drawings Figure 1 is a rear face elevation of the corner of a frame, showing the locking staple therefor; Fig. 2 a cross 45 section on line *a* of Fig. 1, looking in the direction of the arrow; Fig. 3 a perspective view of the abutting end faces of the corner of a frame, showing the interlocking tongue and groove; Fig. 4 a front face view of the 50 corner of a frame, showing the locking staple applied thereto, with an ornamental head, for the staple; Fig. 5 a side elevation of the locking staple of the invention, with an ornamental head thereon; and Fig. 6 a 55 side elevation of a modified form for the staple of the invention, as to the entering

ends of the staple legs; Fig. 7 is an elevation of the frame corner with the staple removed.

The frame can be of any suitable formation 60 and size, having side pieces 1 and end pieces 2, with a corner 3, for each side and end piece, formed on an angle, as shown in Figs. 1 and 4. The side piece 1, as shown, has a tongue 4 across the corner 3, and the end 65 piece 2 has a groove 5 across the corner 3, which tongue and groove are in coinciding planes, so that, when the tongue is entered into the groove, the front and rear faces of the side and end pieces will be flush, and the 70 interlock of the tongue and groove will hold the corner against displacement forward or backward, giving a fixed connection between the pieces at the corner.

The abutting faces of the corners 3 of the 75 frame pieces are brought in close contact by the staple of the present invention, which staple is formed with an end bar 6 and legs 7; and the staple is made from spring wire or other suitable material, so as to give the staple a draw action, for which purpose the legs 80 of the staple are inclined inwardly, as clearly shown in Figs. 2, 5 and 6. The entering end 8 of each staple, as shown in Figs. 2 and 5, is rounded or curved so as to facilitate the entering of the legs into holes 9 extending into the body of the frame pieces on each side of the joint line, as shown in Figs. 1 and 2; and each hole 9, in order to give an in-draw action to the legs of the staple, is of a 85 slightly greater diameter in cross section than the diameter of the legs of the staple, with the distance between the holes the same as the distance between the ends of the legs 90 of the staple, for the wall of each hole, adjacent to the edge of the corner, to furnish a bearing face engaged by the end of the entered staple leg, so that as the staple is forced home, the incline of the legs bearing 95 against the inner face of the hole will serve to draw together the abutting faces of the pieces at the corner 3, as shown in Figs. 1 and 2. Each leg of the staple, instead of having a curved rounded entering end 8, can have an 100 end 10, as shown in Fig. 6, which end has an inner curved face to facilitate the entering of the legs of the staple into the holes 9, to effect a draw action by which the corner joint 105 will be made close, as with the staple, having the end 8 for each leg, of Figs. 2 and 5.

The arrangement of Fig. 1 shows the locking staple for the joint at the corner applied

to the rear face of the frame, but said staple could be applied to the front face of the frame by having a fancy or ornamental head or plate 11 fixed to the end or cross bar of the 5 staple, as shown in Figs. 4 and 5; and when applied to the front face of the frame at the corner, the staple, through the spring legs 7, will act and draw together the abutting faces of the frame pieces at the corner, as de- 10 scribed for the action of the staple in the construction of Fig. 1, so that, whether applied to the rear face, or the front face of the frame, the locking staple of the present invention draws together the abutting faces of 15 the frame corner, and holds the corner against endwise slipping. It will be seen that by means of the interlocking tongue and groove, and the locking staple of the present invention, a close joint is formed at each cor- 20 ner of the frame, and the corner is held against slipping, either edgewise or flatwise, making a complete and perfect corner for the frame.

While it is preferred to have the entering 25 ends of the legs of the locking staple formed rounded, or with a curved inner face, it will be understood that the rounding or curving of the entering end of each staple can be dis- 30 pensed with, so long as the staple legs have a slight inclination toward each other, and are capable of being entered into the receiving holes 9, formed therefor in the body of the frame pieces. The cross bar of the staple can be entered into a cross groove between 35 the holes, so that the cross bar, with the cross groove, will prevent corner sliding of the abutting faces.

The corner of the present invention, with the interlocking groove and tongue and the 40 locking staple, enables a manufacturer of frames to send the frames to dealers, customers and users in a knock-down condition, as no skill is required in securing the corners,

it only being necessary to bring together the abutting faces and enter the locking staples 45 into the receiving holes.

What I claim as new and desire to secure by Letters Patent is:

1. A frame corner having on one abutting face a tongue, and in the opposite abutting face a groove adapted to receive the tongue, for the tongue and groove to maintain the corner in place against flatwise slipping, in combination with a locking staple formed of a cross bar and a pair of legs and made of 50 spring material, each leg having an inward inclination and entered into a receiving hole in the frame corner, substantially as described.

2. A frame corner having on one abutting face a tongue and in the opposite abutting face a groove adapted to receive the tongue, for the tongue and groove to maintain the corner in place against flatwise slipping, in combination with a locking staple formed of 55 a cross bar and a pair of legs and made of spring material, each leg having an inward inclination and a curved entering end and entered into a receiving hole in the frame corner, substantially as described.

3. A frame corner having on one abutting face a tongue and in the opposite abutting face a groove adapted to receive the tongue, for the tongue and groove to maintain the corner in place against flatwise slipping, in combination with a locking staple formed of a cross bar and a pair of legs and made of 75 spring material, each leg having an inward inclination and entered into a receiving hole in the frame corner, with the entered holes 80 larger in cross diameter than the cross diameter of the legs, substantially as described.

WILLIAM GOODROW.
